UNITED STATES PATENT OFFICE.

RUDOLPH E. MORTON, OF CLEVELAND, OHIO.

TRACTION-ENGINE.

1,126,552.

Specification of Letters Patent.

Patented Jan. 26, 1915.

Application filed May 1, 1912, Serial No. 684,375. Renewed October 1, 1914. Serial No. 864,532.

To all whom it may concern:

Be it known that I, RUDOLPH E. MORTON, a citizen of the United States, residing at Cleveland, in the county of Cuyahoga and State of Ohio, have invented new and useful Improvements in Traction-Engines, of which the following is a specification.

This invention relates to certain new and useful improvements in traction engines.

One of the objects of the invention is to provide a traction engine having four driving wheels materially increasing the traction efficiency of, and consequently reducing the weight usually required in machines of this 15 character; and also insuring a high efficiency, adaptability and long life.

A further object is to provide a traction engine provided with four driving wheels capable of being steered in unison, whereby 20 the machine may be operated in a smaller space than the ordinary machines of this character, the front and rear wheels will always "track" or follow in the track of each other, and the machine may run backward 25 as well as forward.

A further object is to provide improved means by which each of the traction wheels is positively and independently driven, whereby all of said wheels are in effect drive 30 wheels.

A further object is to provide improved means for applying the driving power directly to the axles on which the traction wheels are mounted, by means of a suitable 35 flexible driving connection.

A further object is to so connect each of the axles of a traction-engine with the frame of the latter, that said axles will swing or turn without changing the tension on the 40 drive chains in steering.

A further object is to provide guides for directing the drive chain into proper relation with the driving elements of the axles, and so mounting said guides that the drive 45 chain will not be materially interfered with in steering.

A further object is to so connect the axles and frame as to efficiently resist the strains encountered in operation.

A further object is to provide an improved form of axle.

The invention will be hereinafter fully set forth and particularly pointed out in the claims.

In the accompanying drawings:—Figure 1 is a top plan view of a traction engine

constructed in accordance with my invention. Fig. 2 is a side view thereof. Fig. 3 is a rear elevation. Fig. 4 is a transverse sectional view on the line 4—4, Fig. 1. Fig. 5 is a longitudinal sectional view illustrating one of the sectional axles, and the means for connecting the same to the frame. Fig. 6 is a detail front elevation of the subframe for connecting the frame axle with the main frame. Fig. 7 is a similar view of the subframe connected with the rear axle. Figs. 8 and 9 are detail perspective views illustrating the means for supporting the guide wheels for the drive chain. Fig. 10 is a longitudinal sectional view of one of said guide wheels and its supporting journal.

Referring to the drawings, 10 designates the main frame of my improved traction engine, which may be of any suitable or preferred construction, the same being illustrated as made up of longitudinal side bars 11 formed of channel irons and united at their ends by end bars 12, said side and end bars being sufficiently braced in any suitable manner. The engine 13 is located at the forward end of the frame and the cab 14 to be occupied by the operator is at the rear end of the frame. The engine 13 is connected by a suitable clutch 15 with the engine shaft 16 mounted to rotate within a suitable transmission case 17 bolted or otherwise secured to the side bars of the main frame 10. On said shaft is mounted shiftable gears 18 of a change speed mechanism, which gears are 20 adapted to mesh with gears 19 on a transmission shaft 20. The clutch 15 and the change speed mechanism may be of any suitable or preferred construction, the clutch being operated by a crank 21 pivotally mounted on the main frame, and connected by a connecting rod 22, to an operating lever 23, pivotally supported in a position to be conveniently reached by the operator within the cab. The shiftable change speed gears 20 are also operated through suitable connections by a hand lever 24 also located conveniently with respect to the operator's position in the cab.

The transmission shaft 20 is provided with a beveled pinion 30 meshing with a bevel gear 31 keyed, or otherwise secured, to a countershaft 32 which is mounted in bearings 33 rigidly bolted or otherwise secured to the side bars 11. Feathered or otherwise slidably secured to the counter shaft 32 is a pinion 35 meshing with a gear 36 keyed

or otherwise secured to a drive shaft 37 mounted in bearings 38 carried by a box or case 39 rigidly secured by bolts, or other suitable means, to the side bars 11. The sides of said box or case 39 are provided with self contained braces or suitable strengthening webs 40 to take up the strains and stiffen the same. Secured to counter shaft 32 is a belt wheel W by means of which my improved traction engine may be operated as a stationary engine in which case the pinion 35 may be shifted out of mesh with gear 36. It is obvious, of course, that when this change is made said wheel W is subject to the same control from the cab, as to speed, etc., as shaft 32.

The traction wheels 41 may be of any preferred type and each provided with a hub 42 keyed, or otherwise secured to rotate with an axle section 43, of the front and rear axles 43', 43", respectively. Each axle is formed of two of such axle sections 43, meeting at their inner ends. These axle sections are each provided with a longitudinal bore through which is passed a rod 45 provided with nuts 46 on its ends, serving to prevent separation of said axle sections, and to resist the end thrust of a differential gearing sustained on the axle sections 43 through which said rods are passed. To the inner end of each axle section 43 of the front and rear axles is rigidly secured in any suitable manner, a bevel gear 47, said bevel gears of the sections of each axle facing each other and forming opposite members of a differential gear. Each bevel gear 47 is provided with a hub portion 48, the hub portions of the two adjacent differential gear members serving as a journal for the sprocket wheel 49 which carries the planetary pinions 50 meshing with the gears 47, and completing the differential gearing. Each axle section 43 is inclosed within a tube or sleeve 51, the inner ends of each sleeve being secured within collars 52, the outer ends of said sleeves extending to the hubs of the wheel 41, and being provided with bands 54 to prevent sand and grit from working down into the moving parts. In order to reduce the friction, suitable roller bearings 56 are provided between the axle sections 43 and the sleeves 51.

The main frame is connected with the front and rear axles by means of trucks. Each truck comprises a subframe formed of end sections 63 united by rods 64, and supporting arms 65, 65' extending from collars 62 and united by transverse yokes 66, 66', said arms 65' being provided with sockets 67 adapted to receive said vertical rods, whereby said subframe is supported. The rods 64 are provided with annular shoulders 69 adapted to bear upon the upper surfaces of the sockets 67 whereby the weight of the main frame and subframe is sup-

ported by the said supporting frame or yoke. By means of this arrangement the subframe may be readily placed in position or removed from sockets 67, as may be desired. The forward truck is connected with the main frame 10 by a ball and socket connection 61, located on one side of the longitudinal median line of the main frame, and the rear truck is connected with the main frame 10 by means of a turntable 62 provided with anti-friction balls, the axis of said turntable being on the other side of said median line. Each truck is provided with a depending lug 70, the lug 70 of the forward truck having a pivotal engagement with the forward end of a radius brace 71, the rear end of which is rigidly secured to the bottom of the case 39. The lug 70 of the rear truck pivotally engages the end of a radius brace 71' provided with diverging arms secured at their forward ends to the bottom of the case 39 near opposite sides thereof. By this means the machine is materially stiffened.

Secured to the drive shaft 37 is a sheave or sprocket wheel 72 formed with two sheave or sprocket sections 73, 73', the former being connected by a flexible drive member or chain 74 with the sheave or sprocket wheel 49 of the front axle, and the latter being connected by a chain 75 with the sheave or sprocket wheel 49 of the rear axle. In order to guide the chains 74 and 75 into and keep them in proper position to engage the sprocket wheels 49, suitable guide wheels 76 are carried by the subframes 63. Said guide wheels are rotatably mounted upon an inclined journal 77 secured to a supporting member 78, and said guide wheels are held on said journals by means of cap members 79. The supporting member 78, journal 77 and cap member 79 are provided with coinciding bores to receive one of the rods 64, the cap member and supporting member being rigidly secured to said rod by means of set screws, or the like. In this connection it will be noted that the axes of the guide wheels 73 are located in a line between the axle and a line running transversely through the pivot point of the respective subframes by which they are carried. In the drawings the axes of the guide wheels are shown as occupying an angle of approximately 15° with relation to lines drawn transversely through the respective pivot points, but this relation may be varied, the essential arrangement being that said guide wheels be located in a line between the pivot and the axle. The angle indicated above being preferably about one half of the maximum angle of the turning of the truck in either direction from its central position, so that the chains will lead in proper direction to sprocket 49, regardless of the degree to which the truck is turned.

is turned, and at the same time the chains are kept at the same degree of tightness, in all positions, so that said guide wheels and the adjacent sprocket wheel 49 all swing on a radius from the same center, namely the pivot of the subframe. By means of this arrangement, in steering the machine, the front and rear axles swing with the respective trucks, thereby insuring perfect and smooth driving of each axle irrespective of its angle with relation to the main frame.

My improved traction engine may be steered in various ways. In the drawings, I have disclosed a steering mechanism of the character described and claimed in a separate application of even date herewith, wherein a rotatable drum 80 is mounted in suitable bearings 81 carried by the box or case 89, said drum being provided with a worm gear 82 engaged by a work shaft 83 extending up into the cab of the engine, and provided with a hand wheel 84 for convenient manipulation. Secured to the respective arms 85 are steering quadrants 86, 85', each provided with a peripheral groove 86 to receive the steering chains. Two steering chains 89, 89' are employed, each being connected to opposite sides of one quadrant 85 adjacent the front axle, and to opposite sides of the other quadrant adjacent the rear axle, said chains being each passed around the drum 80, one over the top and the other beneath the drum. The arrangement is such that the chains cross each other in advance of the drum 80, in such manner that they will be free from interference with each other as the positions of the axles change. By operating the worm shaft 83 the drum 80 is activated in one direction or the other, as the case may be, causing the two axles to swing simultaneously in different directions, thereby turning the machine which may be effected in a comparatively small space. In this connection it will be noted that the quadrants 85 are concentric with the pivots of the respective subframes, and by means of this relative arrangement of the parts, a pulling action exerted upon one side of either of the steering quadrants 85 will, because of the great leverage obtained, swing the respective subframe upon its pivot. In this manner the machine is steered. By connecting the steering quadrants to the axle through the yokes and arms of the trucks, said yokes and their contiguous axles are braced or stiffened and at the same time any pull upon the steering chain is exerted against the axle as well as against the steering arms, thereby greatly increasing the effectiveness of said steering chains. By this arrangement, also, the steering chains are connected in such manner that they do not slacken or tighten in the steering of the machine.

The operation of the machine is as fol-

lows:—The engine 13 is started in the usual manner, and when the desired speed gears have been thrown into mesh by manipulation of lever 23, the clutch is thrown into engagement through manipulation of lever 21. The result of these manipulations is to impart movement to the drive shaft 37 through the intermediate gearing and shafts. The drive shaft 37, through the sprocket section 73, 73', and chains 74, 75, 75' imparts movement to the sheaves or sprocket wheels 49, which through the differential connections with the axles, effects rotation of the traction wheels 41. Thus it will be seen that each of said traction wheels 80 is independently and positively driven, advantage being taken of the entire weight of the load to secure traction and steering effect, insuring that the machine will be propelled. This is of particular advantage in travelling over plowed fields, loose and sandy soil, or in mud. It will be further noted that by arranging the engine main shaft and the transmission shaft longitudinally of the machine, and mounting the main frame upon subframes, which in turn are carried by the axles, transverse strains are practically eliminated from the engine, whereby the life thereof will be materially lengthened, and said engine may be operated in places heretofore considered inaccessible or undesirable because of the injuries likely to result from such strains.

It will be noted that while I have shown and described my invention as being particularly applicable for a machine of the type commonly known as a traction engine, I do not desire to limit myself in this particular, as my said invention may also be used as a motor truck, or as an automobile, without departing from the spirit of the invention herein involved.

Having thus explained the nature of my invention and described an operative manner of constructing and using the same, although without attempting to set forth all of the forms in which it may be made, or all of the forms of its use, what I claim is:—

1. A traction engine comprising a main frame, axles, wheels supporting said axles, spaced apart supporting arms carried by one of said axles, independent and detachable pivoting means connected to swing with said arms and engaging said main frame, means for connecting the other axle to said main frame, and means carried by said main frame for driving said axles.

2. A traction engine comprising a main frame, axles, wheels supporting said axles, supporting arms carried by said axles, sub-frames independent of said supporting arms, said arms and sub-frames being provided with complementary means for supporting the latter, means for pivotally connecting said sub-frames with the main frame.

frame, and means for applying power to said wheels.

3. A traction engine comprising a main frame, axles, wheels supporting said axles, 5 supporting arms carried by said axles, sub-frames independent and detachable of said supporting arms and carried by the latter, the ends of said sub-frames being provided with means pivotally engaging said main 10 frame, and means for applying power to said wheels.

4. A traction engine, comprising a main frame, axles, wheels supporting said axles, a truck including supporting arms carried 15 by one of said axles, and a subframe provided with spaced apart rods engaged by said arms, whereby said subframe is supported, means carried by the main frame for driving said axle, means for pivotally connecting said subframe and said main frame, and means for connecting said main frame and the other axle.

5. A traction engine comprising a main frame, axles, wheels supporting said axles, 25 supporting arms carried by one of said axles, a sheave for driving the last mentioned axle, a sub-frame independent of said supporting arms, said arms and sub-frame being provided with complementary 30 means for supporting the latter, means for pivotally connecting said sub-frame with the main frame, a flexible member for driving said sheave, means carried by the main frame for actuating said flexible member, 35 means carried by said sub-frame for guiding said flexible member, and means for connecting said main frame and the other axle.

6. A traction engine comprising a main 40 frame, axles, wheels supporting said axles, supporting arms carried by one of said axles, a sub-frame independent of and detachable from said supporting arms and carried by the latter, the end of said sub-frames being 45 provided with means pivotally engaging said main frame, a sheave for driving the last mentioned axle, a chain for driving said sheave, means carried by the main frame for actuating said chain, guide wheels carried 50 by said sub-frame, the space between said guide wheels being in alignment with said sheave and the pivoting means, and means for connecting said main frame and the other axle.

55 7. A traction engine comprising a main frame, axles, wheels supporting said axles, supporting arms carried by one of said axles, a sub-frame provided with spaced apart rods, said arms and rods being provided 60 with complementary means for supporting the sub-frame, means for pivotally connecting said sub-frame and said main frame, a sheave for driving the last mentioned axle, a chain for driving said sheave, means carried 65 by the main frame for actuating said

chain, supporting members carried by said rods and provided with journals, guide wheels for said chain rotatably mounted on said journals, and means for connecting the main frame and the other axle.

8. A traction engine comprising a main frame, axles, wheels supporting said axles, a subframe supported by one of said axles and provided with spaced apart rods, means for pivotally connecting said subframe and 75 said main frame, a sheave for driving the last mentioned axle, a chain for driving the said sheave, means carried by the main frame for actuating said chain, means for connecting the main frame and the other 80 axle, supporting members provided with inclined journals, said supporting members and journals having coinciding bores to receive said rods, and chain-guide wheels mounted on said journals.

85 9. A traction engine comprising a main frame, axles, wheels supporting said axles, a subframe supported by one of said axles and provided with spaced apart rods, means for pivotally connecting said subframe and 90 said main frame, a sheave for driving the last mentioned axle, a chain for driving the said sheave, means carried by the main frame for actuating said chain, means for connecting the main frame and the other 95 axle, supporting members carried by said rods and provided with inclined journals, chain-guide wheels mounted on said journals, and cap members also carried by said rods and cooperating with said supporting 100 members to retain said guide wheels on said journals.

10. A traction engine comprising a main frame, axles, wheels supporting said axles, supporting arms carried by one of said axles, 105 a sub-frame provided with spaced apart rods, said arms and rods being provided with complementary means for supporting the sub-frame, means for pivotally connecting said sub-frame with the main frame, means 110 carried by the main frame for driving said axle, and means for connecting said main frame and the other axle.

11. A traction engine comprising a main frame, axles, wheels supporting said axles, 115 supporting arms carried by one of said axles and provided with sockets, a subframe provided with rods secured within said sockets, said rods having shouldered portions engaging the tops of said sockets, means for pivotally connecting said subframe and the main 120 frame, means carried by the main frame for driving said axle, and means for connecting said main frame and the other axle.

12. A traction engine comprising a main 125 frame, axles, wheels supporting said axles, supporting arms carried by one of said axles, a subframe supported by said arms, a ball and socket connection between said subframe and said main frame, means for 130

connecting said main frame and the other axle, and means carried by said main frame for driving the first mentioned axle.

13. A traction engine comprising a main frame, axles, wheels supporting said axles, supporting arms carried by one of said axles, a drive chain operatively connected with the last mentioned axle, a subframe supported by said arms, means for pivotally connecting said subframe and said main frame, means for actuating said chain, spaced apart guides for said chain carried by said subframe and located between said axle and said pivotal connection, and means for connecting said main frame and the other axle.

14. A traction engine comprising a main frame, axles, wheels supporting said axles, supporting arms carried by one of said axles, a subframe rigidly supported by said arms, means for pivotally connecting the main frame and the upper end of said subframe, means connected with the main frame for pivotally engaging the lower end of said subframe, means for driving said axle, and means for connecting said main frame and the other axle.

15. A traction engine comprising a main frame, axles, wheels supporting said axles, oppositely disposed trucks supported by said axles and provided with supporting arms, subframes supported by said arms, means for pivotally connecting the main frame and said subframes on opposite sides of the longitudinal median line of the main frame, and means carried by the main frame for driving both axles.

16. A traction engine comprising a main frame, axles, wheels supporting said axles, oppositely disposed trucks supported by said axles and provided with supporting arms, subframes supported by said arms, means for pivotally connecting the main frame and one of said subframes, means for providing a universal connection between said main frame and the other subframe, the connections between the main frame and subframes being on opposite sides of the longitudinal median line of the main frame, and means carried by the main frame for driving both axles.

17. A motor vehicle comprising a main frame, axles, wheels supporting said axles, drive chains operatively connected with said axles, trucks supported by said axles, means for pivotally connecting said main frame and said trucks, spaced apart rods carried by each truck, guide wheels for each chain carried by said rods and located between the pivotal connection and the axle of the respective trucks, and means for actuating said drive chains.

18. A motor vehicle comprising a main frame, axles, wheels supporting said axles, a truck secured to one of said axles and provided with spaced apart arms, means for

pivotally connecting said main frame and said arms, a drive chain for the last mentioned axle, spaced apart guide wheels carried by said truck and located between the axle and said pivotal connection, means for actuating said chain, and means for connecting the main frame and the other axle.

19. A traction engine comprising a main frame, axles, wheels supporting said axles, trucks carried by said axles and provided with supporting arms, subframes carried by said arms, means for pivotally connecting said main frame and the upper end of said subframes, braces carried by the main frame and pivotally engaging the lower ends of said subframes, and means carried by said main frame for driving said axles.

20. A traction engine comprising a main frame, axles, wheels supporting said axles, a detachable subframe secured to one of said axles and formed of end plates connected by spaced apart rods, means for driving said axle, means for pivotally connecting said main frame and one end plate of said subframe, and means for connecting the other axle to said main frame.

21. A traction engine comprising a main frame, axles, wheels supporting said axles, a subframe secured to one of said axles and formed of end plates connected by spaced apart rods, means for driving said axle, means for providing a universal connection between said main frame and said subframe, and means for connecting the main frame and the other axle.

22. A traction engine comprising a main frame, axles, wheels on said axles, a sheave on one of said axles, a flexible member for driving said sheave, means for actuating said flexible member, spaced apart rods supported by the last mentioned axle, inclined journals supported by said rods adjacent said sheave, and guide wheels mounted on said inclined journals and engaging said flexible member.

23. A traction engine comprising a main frame, axles, wheels on said axles, a sheave on one of said axles, a flexible member for driving said sheave, means for actuating said flexible member, spaced apart inclined journals supported adjacent said sheave, guide wheels mounted on said inclined journals engaging said flexible member, and cap members engaging said inclined journals to retain said guide wheels in position.

24. A traction engine comprising a main frame, an axle formed of sections arranged in alinement, traction wheels secured to said axle sections, means for taking up the end thrust of said axle section, independent spaced apart supporting arms carried by said axle, a sub-frame independent of said supporting arms, said sub-frame and arms being provided with complementary means for supporting the former, means for pivot-

ally connecting said sub-frame with the main frame, means for driving said axle sections independently, a second axle secured to said main frame, and wheels supporting the last mentioned axle.

25. A traction engine comprising a main frame, an axle formed of sections arranged in alignment, traction wheels secured to said axle sections, means for resisting the end thrust of said axle sections, supporting arms carried by said sectional axle, a subframe provided with rods engaged by said arms, whereby said subframe is supported, means for pivotally connecting said main frame and said subframe, means for driving said axle sections independently, a second axle secured to said main frame, and wheels supporting the last mentioned axle.

26. A traction engine comprising a main frame, an axle formed of sections arranged in alignment, traction wheels secured to said axle sections, means for preventing separation of said axle sections, supporting arms carried by said axle, a sub-frame provided with spaced apart rods, said arms and rods being provided with complementary means for supporting the sub-frame, means for pivotally connecting said main frame and said sub-frame, differential gearing for independently driving said axle sections, a sheave for actuating said differential gearing, a chain for driving said sheave, means carried by the sub-frame for guiding said chain, a second axle connected with the main frame, and wheels supporting the last mentioned axle.

27. A traction engine comprising a main frame, axles each formed of sections arranged in alignment, means for preventing separation of the sections of each axle, traction wheels secured to said axle sections, oppositely disposed arms supported by said axles, sub-frames provided with spaced apart rods, said arms and rods being provided with complementary means for supporting the sub-frames, means for pivotally connecting the main frame and said sub-frames, and means for independently driving the axle sections.

28. A traction engine comprising a main frame, axles each formed of sections arranged in alignment, traction wheels secured to said axle sections, means for preventing separation of the sections of each axle, arms supported by said axles, sub-frames carried by said arms, means for

pivotally connecting the main frame and one of said subframes, means for providing a universal connection between the main frame and the other subframe, and means for independently driving said axle sections.

29. A traction engine comprising a main frame, axles each formed of sections arranged in alignment, traction wheels secured to said axle sections, means for preventing the sections of each axle from parting longitudinally, sleeves surrounding the sections of each axle, supporting arms carried by said sleeves, sub-frames independent of said arms, said sub-frames and arms being provided with complementary means for supporting the former, means for pivotally connecting the sub-frame with the main frame, and means for independently driving said axle sections.

30. A traction engine comprising a main frame, two axles, each formed of sections arranged in alignment, traction wheels secured to said axle sections, means for preventing the sections of each axle from parting longitudinally, supporting arms carried by said axles, subframes carried by said arms, means for pivotally connecting the main frame and said subframes, braces carried by the main frame and pivotally engaging the lower ends of said subframes, and means for independently driving said axle sections.

31. A traction engine comprising a main frame, two axles each formed of sections arranged in alignment, traction wheels secured to said axle sections, means for preventing longitudinal separation of the sections of each axle, supporting arms carried by said axles, subframes carried by said arms, means for pivotally connecting the main frame and said subframes, diverging braces pivotally engaging the lower end of one of said subframes, the diverging ends of said braces being rigidly connected with the main frame, an independent brace connecting the other subframe with the main frame, and means for independently driving said axle sections.

In testimony whereof I have hereunto set my hand in presence of two subscribing witnesses.

RUDOLPH B. MOERTON.
